UNITED STATES PATENT OFFICE.

BERNARD B. BRADY AND ANDREW B. McCANNA, OF CHICAGO, ILLINOIS.

CAR-STARTER.

SPECIFICATION forming part of Letters Patent No. 358,642, dated March 1, 1887.

Application filed November 23, 1886. Serial No. 219,564. (No model.)

To all whom it may concern:

Be it known that we, BERNARD B. BRADY and ANDREW B. McCANNA, citizens of the United States of America, residing at Chicago, 5 in the county of Cook and State of Illinois, have invented certain new and useful Improvements in Car-Starters, of which the following is a specification, reference being had therein to the accompanying drawings.

- 10 This invention relates to devices for assisting the horses in starting a car; and it has for its object to provide an arrangement by which the driver, by operating the brakes, will compress a spring, the elastic force of which again 15 will be utilized for starting a car; also, to provide friction-wheels brought in contact by the brake-operating mechanism and tending to utilize the momentum of the car for compressing such spring.
- 20 Our invention therefore consists of the novel devices and combinations of devices hereinafter described, and specifically claimed.

In the accompanying drawings, Figure 1 represents a longitudinal sectional elevation 25 of the platform and running-gear of a car embodying our improvements and in position as when the car is in motion; Fig. 2, a similar view of the same in position as after applying the brakes; Fig. 3, a plan view of the running-gear, and Figs. 4 and 5 a longitudinal section and edge view of the segmental starting-wheel.

Corresponding letters in the several figures of the drawings designate like parts.

- 35 A and A' denote the axles, and B the car-wheels, mounted thereon. Upon the middle of each axle is also rigidly mounted a ratchet-wheel, C, and a friction-wheel, D. A segmental sprocket-wheel, E, is loosely sleeved 40 upon each axle A by bifurcated arms e and V- straps d, that embrace the ratchet-wheel C, and a pawl, F, is pivoted between the arms e, engaging with the teeth of the ratchet-wheel C.

G G are the brake-shoes, each pair connected 45 by a brake-beam, H, and suspended to the car body by links in the usual manner.

Between brackets I, secured upon the middle of each brake-beam, is pivoted a shaft, i, upon which is rigidly mounted a friction-wheel, J, and a sprocket-wheel, K. The fric-

tion-wheel J, being in line with wheel D, will be rotated by frictional contact therewith, which rotating movement will be imparted to sprocket-wheel K, that again is in line with segmental sprocket-gear E.

A spiral spring, L, is placed between plates M M', that slide upon longitudinal rods fixed between brackets N N' of the car-body. A rod, O, passed through the spring L and through an opening in plate M, is coupled 60 with its end to plate M', and another rod, O', also passed through spring L and through an opening in plate M', is coupled with its end to plate M, and while rod O has coupled the end of a chain or link belt, P, which, after passing 65 over segmental sprocket-gear E and sprocket-wheel K of one end of the car, is secured with its opposite end to brake-staff Q, the rod O' has coupled a similar chain or link belt, R, that, after passing over the segmental sprocket-gear E' and sprocket-wheel K' of the opposite end of the car, is secured to brake-staff S.

The friction-wheels J have each two diametrically-opposite arc-shaped notches, j, that, while the car is in motion, are on a diagonal 75 position, as shown in Fig. 1, but will bring the wheel J into frictional contact with wheel D; this wheel J will be rotated such portion of a revolution until the notches j are brought in horizontal line with wheel D, as shown in 80 Fig. 1.

The car moving in the direction indicated by arrow in Fig. 1, the driver, for stopping, will turn staff S, when the tension of chain R will rotate sprocket-wheel K' to compress 85 spring L, and at the same time he will pull wheel J into frictional contact with wheel D to rotate therewith, whereby the momentum of the car will help the driver, compressing the spring until the notch j engages the rim 90 of the wheel, and then, with a further turning of the brake-staff, the brake-shoes will be brought to bear against their respective car-wheels, stopping further motion of the car; and while thus the wheels J K are turned and 95 the spring L is compressed, the segmental sprocket E' is also turned by the chain or link belt R engaging its teeth in a manner that the sudden releasing of the brakes will release the full elastic force of the spring to act upon such 100

segmental sprocket E', which, by the engagement of its pawl F' with ratchet-wheel C, will transmit such force upon the axle to be rotated thereby in the forwardly-moving direction, and will thus assist the horses in starting the car.

As will be noticed, the friction-wheels D and J are herein applied for the purpose of assisting the driver in compressing the spring 10 by the momentum of movement of the car; but yet by the great leverage power the driver can exert for winding the chain upon the staff he can sufficiently compress the spring L to start or assist the horses in starting the car, 15 and therefore in certain instances these friction-wheels D and J can be omitted, and when thus omitted the two break-beams may be connected in any well-known manner to operate all the brake-shoes simultaneously by the turning of either brake-staff.

The improvement herein described will be adapted as well for a cable-car as for a horse-car.

We are aware that car brakes and starters 25 have been made with a spring under the car and a chain connecting to the brake-shaft, and having a lever for operating the axle positively connected with and forming a part of said chain, and that friction-wheels for aiding in 30 stopping the car have been used directly upon the ground-wheels, to which friction-wheel the brake-shoe is secured; and we do not claim such, as in our invention the chain and axle-lever are not positively connected, nor are the 35 friction-wheels applied to the ground-wheels, nor do they have the brake-shoes attached to them; and in no previous devices, so far as we are aware, have separate friction-wheels been applied to the car-axle, nor have the friction- 40 wheels upon the brake-shaft been provided with notches for limiting their motion.

What we claim is—

1. In a car-starter, the combination, with the 45 brake-staff, a spring secured under the body of the car, and a sprocket-chain connecting said spring with said brake-staff, of a sprocket-wheel around which the sprocket-chain passes, a ratchet-wheel fixed on an axle of the car, and a segmental sprocket-gear loosely mounted on

50 said axle and having a pawl to engage the ratchet-wheel, said segmental gear being engaged with the sprocket-chain.

2. The combination, with the brake-beam, friction-wheels, as described, for braking, and brake-staff, of a spring secured under the 55 body of the car, a ratchet-wheel fixed upon the axle, a segmental sprocket-gear loosely sleeved upon such axle and having a pawl engaging the ratchet-wheel, a sprocket-wheel pivoted between brackets on the brake-beam, and a 60 sprocket-chain engaging the segmental gear and passing round the sprocket-wheel, said chain being attached at one end to the brake-staff and at the other to the spring under the body of the car. 65

3. The combination, with the brake-beam and brake-staff of a car, of a spring secured under the car-body, a friction-wheel and ratchet-wheel rigidly mounted upon the axle, a segmental sprocket-wheel loosely sleeved upon 70 the axle and provided with a pawl engaging the ratchet-wheel, a sprocket-wheel and friction-wheel pivoted between brackets of the brake-beam, and a chain connected with the spring and passed over and around the segmental 75 gear and sprocket-wheel, all substantially as set forth, to operate as specified.

4. The combination, with the brake-beam and brake-staff of a car, of a spring secured under the car-body, a friction-wheel and ratchet-wheel rigidly mounted upon the axle, a segmental sprocket-gear loosely sleeved upon the axle and provided with a pawl engaging the ratchet-wheel, a sprocket-wheel and friction-wheel pivoted between brackets of the brake-beam, such friction-wheel having notches for 80 limiting its movement, and a chain connected with the spring and passed over and around the segmental gear and sprocket-wheel, all substantially as set forth, to operate as specified. 85

In testimony whereof we affix our signatures in presence of two witnesses.

BERNARD B. BRADY.
ANDREW B. McCANNA.
